CLAIM

The ornamental design for motor housing for canister type electric vacuum cleaner, as shown and described.

DESCRIPTION

FIG. 1 is a front perspective view of a motor housing for canister type electric vacuum cleaner showing our new design, the broken lines are for illustrative purposes only and form no part of the claimed design;

FIG. 2 is a top plan view thereof;

FIG. 3 is a rear elevational view thereof;

FIG. 4 is a front elevational view thereof;

FIG. 5 is a right side elevational view thereof; and

FIG. 6 is a left side elevational view thereof.

The material shown in broken lines is environmental material and not part of our design.

FIG. 1.

FIG. 2.

FIG. 3.FIG. 4.FIG. 5.

FIG. 6.
